UNITED STATES PATENT OFFICE.

MORITZ D. SCHWARTZ, OF NEW YORK, N. Y.

CHANDELIER.

1,219,171.

Specification of Letters Patent.

Patented Mar. 13, 1917.

Application filed October 2, 1916. Serial No. 123,310.

To all whom it may concern:

Be it known that I, MORITZ D. SCHWARTZ, a citizen of the United States, and a resident of the city of New York, in the county 5 of Kings and State of New York, have invented certain new and useful Improvements in Chandeliers, of which the following is a specification.

The present invention relates to fixtures 10 for electric, gas and other light systems; it pertains more particularly to a chandelier for the indirect lighting systems, in which, as well-known, the lamps are supported at some distance from the ceiling and positioned 15 beneath the lamps are inverted dome-shaped shades or canopies, which are held suspended by chains, or other means, that are attached at their upper ends to the structure at a point adjacent to the ceiling. 20 The difficulty experienced with the indirect lighting system has been that the dome-shaped shades cannot be properly cleaned, and particularly can their inner faces not be cleaned without the use of a ladder, or some other support, which the attendant has to 25 ascend in order to reach the shades. While it may be comparatively easy to carry around a ladder or similar support in large halls, it is very inconvenient to do so in crowded 30 apartments, offices, workshops, etc. The result is that, usually, only the outer surfaces of the shades are cleaned as they can be reached by the aid of dusters, brushes, etc., without the use of a ladder; on their inner 35 faces, however, dust and other foreign matter is allowed to collect, thereby greatly impairing the transparency or translucency, as the case may be, of the shades, and thus the lighting power of the lamps.

40 The main object of this invention is to provide a lighting fixture for indirect systems, the shade of which is so mounted upon its supporting chains that it can be conveniently and readily lowered for cleaning purposes, etc.

45 Another object of the invention is to so construct a chandelier that it can be manufactured on a commercial scale, or in other words, in such a manner that it is not so difficult to produce as to be beyond the reasonable cost of such a fixture.

With these and other objects in view, which will more fully appear as the nature of the invention is better understood, the same consists in the combination, arrangement, and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

55 60 65 Two of the many possible embodiments of the invention are illustrated in the accompanying drawings, in which:

Figure 1 is a front elevation of a lighting fixture constructed in accordance with the 70 principles of the present invention; Fig. 2 is a vertical longitudinal section of one of the connections between the shade and a supporting chain, on a larger scale; Fig. 3 is a section taken on line 3—3 of Fig. 2; Fig. 4 75 is a top plan view of a modified shade; Fig. 5 is a section taken on line 5—5 of Fig. 4, on a larger scale; and Fig. 6 is a section taken on line 6—6 of Fig. 5.

80 Referring now more particularly to Figs. 1 to 3, inclusive, the numeral 10 indicates a cup-shaped member, that is attached in any suitable manner to a support 11 on the ceiling, upon said support being mounted a socket (not shown), from which lead electric 85 conductors to a lamp 12. This lamp is screwed into a socket 13, that is fixedly secured to a tubular member 14, through which the conductors are led. The tubular member is connected by links 15 with a tubular body 16, that is fastened in any suitable manner to the cup-shaped member 10, and carries hooks 17, which form supports for chains 18, the lower ends of which support 90 a dome-shaped, inverted shade or canopy 19, which may be of opaque material when an indirect lighting system is used, or may be translucent where a semi-indirect system is desired.

95 100 The connection between each chain and the shade is made by extensible means, which are all alike, so that herein only one of the

same will be described. The extensible means is shown in detail in Figs. 2 and 3 of the drawings, and comprises a cylindrical casing 20, having a detachable cover 21. 5 Upon the casing is formed an eye 22, into which is hooked the lower end of a chain 18. Longitudinally there extends through the casing a spindle 23, upon which is rotatably mounted a drum 24. Upon this drum is 10 wound a flexible means, such as a cord or wire 25, one end of which is attached in any suitable manner to the drum, while its other end projects through an aperture 26 in the cylindrical portion of the casing, and has 15 attached thereto a hook 27, which extends through an eye 28, that is in any suitable manner secured to the shade 19. Within the drum is disposed a spiral spring 29, its inner end being fastened to the hub 30 of 20 the drum, while its outer end is made fast to the casing. For the latter purpose there may be screwed to the detachable cover 21 a bolt 31, around which the outer end of the spring is drawn.

25 Usually the shade 19 is supported by three chains, and consequently there are three of the extensible connections provided.

The operation of this device is as follows: The normal positions of the elements of the apparatus are shown in Figs. 1 to 3, inclusive, in which the shade 19 is in its raised, operative position, and the springs 29 are in their extended or unwound state, holding the cords or wires 25 wound upon their respective drums. The tension of the springs and the weight of the shade are such that the latter will be kept normally in its raised position. If it is intended to lower the shade for cleaning purposes, etc., it is taken hold of by some means and pulled downward. As the shade is being lowered, the cords or wires 25 are simultaneously unwound from the drums. In unwinding, the drums rotate in the direction of the arrow 40 shown in Fig. 3 of the drawings, with the result that the springs 29 are wound up, or in other words they are put under tension. The operator, while cleaning the shade, holds the same in its lowered position 45 against the action of the springs 29. After the work has been finished, the shade is permitted to ascend slowly. The ascent of the shade is automatic and is effected by the springs 29, which, as the shade is released, 50 have a tendency to return to their normal, unwound state, thereby rotating the drums 24 in a direction opposite to that of the arrow shown in Fig. 3 of the drawings, and 55 winding the cords or wires 25 upon the said drums.

60 The modification shown in Figs. 4 to 6, inclusive, differs only slightly from the device above described. In this case there is

attached to the rim of the shade an endless tube 32, for instance, by clips 33. This tube 65 is provided with three cylindrical enlargements 34, which may be either made integral with the tube or they may be made separate and fixedly attached to the tube, for instance, by screws 35. Within each of these 70 enlargements is rotatably mounted a drum 36, corresponding to the drums 24 above described. Upon each of these drums is wound a cord or wire 25', one end of which is attached to the drum, while its other end extends through an aperture 37 in the respective enlargement 34 and carries a hook 38, which is engaged with one of the chains 18. With each of the drums is associated a helical spring 39, extending from enlargement 80 75 to enlargement, and one of its ends being hooked into or otherwise attached to the drum, while its other end is fastened to the tube 32.

The operation of this device is in all respects identical with that of the one above described. When the chandelier 19 is being lowered, the cords or wires 25' are unwound from their drums 36, which, as they rotate, wind up the springs 39. If the shade is released, the springs return to their normal state, in which they wind up the cords or wires 25' upon their drums.

What I claim is:

1. A lighting fixture for indirect lighting systems comprising a support adapted to be secured to a ceiling or the like, a plurality of flexible supporting members depending therefrom, an inverted dome-shaped shade, an endless tube secured to said shade having 95 a number of cylindrical enlargements corresponding to the number of flexible supporting members, a drum rotatably mounted in each enlargement, a cord attached to each drum and wound thereupon and secured to its respective flexible member, and a plurality of springs within said tube, each spring 100 being attached to one drum and to said tube.

2. A lighting fixture for indirect lighting systems, comprising a support adapted to be secured to a ceiling or the like, a plurality of flexible supporting members depending therefrom, an inverted dome-shaped shade, a plurality of drums corresponding to the number of said flexible supporting members 110 105 rotatably mounted upon said shade, a cord attached to each drum and wound thereupon and secured to its respective flexible member, and a spring attached to each drum and said shade.

3. A lighting fixture for indirect lighting systems, comprising a support adapted to be secured to a ceiling or the like, a plurality of flexible supporting members depending therefrom, an inverted dome-shaped shade, 115 120 a plurality of cylindrical casings corre-

sponding to the number of said flexible supporting members attached to said shade, a drum rotatably mounted in each casing, a cord attached to each drum and wound thereupon and secured to its respective flexible member, and a spring attached to each drum and said shade.

Signed at New York, in the county of New York, and State of New York, this 26th day of September, A. D. 1916.

MORITZ D. SCHWARTZ.
